UNITED STATES PATENT OFFICE.

EMIL WOERTH, OF BROOKLYN, NEW YORK.

AMUSEMENT APPARATUS.

No. 909,500.

Specification of Letters Patent.

Patented Jan. 12, 1909.

Application filed May 7, 1908. Serial No. 431,314.

To all whom it may concern:

Be it known that I, EMIL WOERTH, a citizen of the United States, residing at Brooklyn, in the county of Kings and State of New York, have invented certain new and useful Improvements in Amusement Apparatus, of which the following is a specification, such as will enable those skilled in the art to which it appertains to make and use the same.

This invention relates to amusement devices or apparatus designed for use at pleasure resorts of various kinds and classes, and the object thereof is to provide an improved device or apparatus of this class designed to travel on a track either inclined or horizontal, or on an inclined surface of any kind or class, and which involves a suitable truck or frame mounted on wheels and on which is placed a rotatable passenger carrier which is geared in connection with one of the axles; a further object being to provide a device or apparatus of the class specified which is adapted to be operated by gravity or by power; and with these and other objects in view the invention consists in an apparatus of the class specified constructed as herein-after described and claimed.

The invention is fully disclosed in the following specification, of which the accompanying drawing forms a part, in which the separate parts of my improvement are designated by suitable reference characters in each of the views, and in which;

Figure 1 is a sectional side view of one form of my improved amusement device or apparatus, and;—Fig. 2 a bottom plan view thereof.

In the practice of my invention, as shown in the drawing, I provide a truck frame or support a , the end portions of which are provided with hangers a^2 , in which are mounted axles b provided with wheels b^2 which may be so formed as to travel on a smooth surface, or on the rails of a suitable track.

Mounted on the truck frame or support a is a rotatable passenger carrier c which, in the construction shown, is circular in form and provided with an internal annular seat c^2 . The truck frame or support a is provided on the opposite sides of the rotatable carrier c , and forwardly and backwardly thereof, in the form of construction shown, with segmental guides and keepers d in which are mounted anti-friction rollers d^2 which are adapted to bear on the sides of the carrier c , and the guides and keepers d serve, in the op-

eration of the apparatus, to hold the carrier c in proper position under all conditions. The truck frame or support a is also provided with an annular plate a^3 which is placed under the carrier c , and the bottom of said carrier is provided with a corresponding annular plate c^3 between which and the plate d^3 are placed anti-friction ball-bearings c^4 . The truck frame or support a is also provided centrally thereof with a tubular bushing e which passes therethrough, and secured to and in the central part of the bottom of the carrier c is a vertically arranged shaft f which passes downwardly through the tubular bushing e and is provided at its lower end with a beveled gear f^2 .

Supported transversely of and beneath the bottom of the truck frame or support a is a horizontal shaft g , on which is slidably mounted a sleeve g^2 , on the opposite ends of which are secured beveled gears g^3 and g^4 , and one of said gears, the gear g^3 as shown in the drawing, is provided with a hub g^5 having an annular groove g^6 .

Pivoted beneath the bottom of the truck frame or support a , as shown at g^7 , is a lever h which ranges longitudinally of said truck frame or support a and is provided at its inner end with a yoke h^2 which fits in the groove g^2 , in the usual manner, and the other end of said lever h is bent upwardly to form an arm h^3 by means of which the lever h may be operated by a party sitting on a seat h^4 at one end of the truck frame or support a . The shaft g is also provided with a sprocket gear i , and one of the axles b with a corresponding sprocket gear i^2 , and mounted on the gears i and i^2 is a drive chain i^3 . One of the wheels b^2 beneath the end of the truck frame or support a on which the seat h^4 is placed is provided with a brake drum j , and secured to the corresponding hanger a^2 and j^2 is a brake band j^3 which passes around the drum j and with which is connected a lever j^4 pivoted at j^5 , and by means of which the brake band j^3 is operated, said lever being also under the control of a party sitting on the seat h^4 .

In the operation of this apparatus, the passengers take their seats in the carrier c , and said carrier is rotated by the movement of the truck, the speed of said truck being controlled by the gearing i , i^2 , i^3 and by the brake operated by the lever j^4 . It will be understood that the truck may be operated by gravity, all that is necessary being to pro-

vide a suitable inclined surface, or said truck may be operated on inclined tracks, the wheels b^2 being so formed as to retain the truck on said tracks, or said truck may be 5 operated by a suitable motor on a perfectly level surface, or on level tracks, all that is necessary being to place the motor on the truck and gear it in connection with one of the axles b . As thus constructed, it will be 10 seen, that the speed of the truck may be easily controlled by the brake device, and that when the truck is given a movement in either direction the carrier c , in which the passengers are placed, is given a rotary motion, and the direction of this motion may be 15 changed at any time by manipulating the lever h so as to alternately throw either of the gears g^3 or g^4 into or out of engagement with the gear f^2 , and the motion or movement 20 thus given to the carrier c , and the passengers therein will be amusing and highly entertaining.

Although I have described my improved amusement apparatus as adapted to be operated by gravity on an inclined surface or on 25 inclined tracks, it will be apparent that a motor may be placed on the truck and used to drive the same and operate the carrier on such inclined surface or inclined tracks as 30 well as when the device is operated on a level surface or on level tracks, and instead of employing a carrier c which is circular in form other forms of carriers may be employed and geared in connection with one of 35 the axles of the truck, and when a motor is employed to drive the truck the carrier or carriers may be geared in connection with the motor instead of in connection with an axle of the truck.

40 My invention is not limited to the exact

details of construction herein shown and described, and various changes therein and modifications thereof may be made, within the scope of the appended claims, without departing from the spirit of my invention or 45 sacrificing its advantages.

Having fully described my invention, what I claim as new and desire to secure by Letters Patent, is:—

1. An apparatus of the class described, 50 comprising a suitable truck, a rotary passenger carrier mounted thereon and geared in connection with one of the axles of the truck, and means for changing the direction of the rotation of the passenger carrier. 55

2. An apparatus of the class described, comprising a suitable truck, a rotary passenger carrier mounted thereon and geared in connection with one of the axles of the truck, and means for changing the direction of the 60 rotation of the passenger carrier, and for controlling the speed of the truck.

3. An apparatus of the class described, comprising a suitable truck, a rotary passenger carrier mounted thereon and geared in 65 connection with one of the axles of the truck, and means for changing the direction of the rotation of the passenger carrier, and for controlling the speed of the truck, said truck being adapted to be operated by gravity on an 70 inclined surface or track.

In testimony that I claim the foregoing as my invention I have signed my name in presence of the subscribing witnesses this 6th day of May, 1908.

EMIL WOERTH.
